UNITED STATES PATENT OFFICE.

JAMES T. COWLEY, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

SPECIFICATION forming part of Letters Patent No. 687,202, dated November 26, 1901.

Application filed July 10, 1901. Serial No. 67,754. (No model.)

To all whom it may concern:

Be it known that I, JAMES T. COWLEY, of Boston, in the county of Suffolk and State of Massachusetts, have invented certain new and useful Improvements in Pneumatic-Despatch-Tube Apparatus, of which the following is a specification.

My invention relates to new and useful improvements in pneumatic-despatch apparatus in which the carriers are transmitted from one end of the line to the other; and its object is to provide a valve located in the suction-tube for regulating the pressure in the system.

My invention consists of certain novel features hereinafter described, and particularly pointed out in the claims.

In the accompanying drawings, which illustrate a construction embodying my invention, Figure 1 is a detail view of the valve-operating mechanism shown in Fig. 2. Fig. 2 is a sectional view of the valve for regulating the pressure in the system.

Like letters of reference refer to like parts throughout both views.

G represents a valve located in the suction-tube F for regulating the pressure in the system and consisting of a cylinder G¹, having a branch G². Within this cylinder is a sleeve G³, having an end closed by a cover G⁴, and passing through the center of the cover G⁴ is a shaft G⁵, having on one end the handle G⁶. This shaft is provided with an enlarged collar G⁷ to hold the shaft G⁵ in place in the cover G⁴. The other end G⁸ of the shaft G⁵ is threaded, and the threaded portion passes through the hub G⁹, having the arms G¹⁰, which extend inside of the valve and are secured by the bolts G¹¹ to the sides of the cylinder G¹, the bolts passing through and connecting the sleeve G¹². The valve G is opened and closed and the air circulation regulated by turning the handle G⁶, thereby raising or lowering the inner cylinder G³, so that by enlarging or diminishing the passage G¹³ more or less pressure is obtained in the system.

Having thus described the nature of my invention and set forth a construction embody-

ing the same, what I claim as new, and desire to secure by Letters Patent of the United States, is—

1. In a pneumatic-despatch-tube apparatus, a valve closed at its outer end to the atmosphere and open at its inner end to the tube for regulating the pressure in the despatch-tube, a screw-threaded shaft, and a stationary nut with which said screw-threaded shaft is adapted to operate for sliding the valve inwardly and outwardly for closing and opening the same.

2. In a pneumatic-despatch-tube apparatus, a valve closed at its outer end to the atmosphere and open at its inner end to the tube for regulating the pressure in the despatch-tube and consisting of a cylinder provided with an internal screw-threaded shaft, and a stationary nut secured to the interior of the valve-casing and with which said screw-threaded shaft is adapted to operate to open and close the valve.

3. In a pneumatic-despatch-tube apparatus, a cylindrical valve closed at its outer end to the atmosphere and open at its inner end to the tube for regulating the pressure in the despatch-tube, and means for moving said valve outwardly and inwardly to open and close the same.

4. In a pneumatic-despatch-tube apparatus, a valve closed at its outer end to the atmosphere and open at its inner end to the tube for regulating the pressure in the despatch-tube and consisting of a cylinder provided with a screw-threaded shaft and a stationary nut having branching arms secured to the interior of the valve-casing and with said nut having said screw-threaded shaft is adapted to operate to open and close the valve.

In testimony whereof I have signed my name to this specification, in the presence of two subscribing witnesses, this 26th day of June, A. D. 1901.

JAMES T. COWLEY.
